UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK G. STEVENS, OF ATTICA, NEW YORK.

TELEPHONE-EXCHANGE SYSTEM.

1,109,617.

Specification of Letters Patent.

Patented Sept. 1, 1914.

Application filed June 23, 1906. Serial No. 323,096.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems and has for its object the improvement and simplification of such systems.

In order to attain my object I make use of a combination of manual and automatic 15 connective apparatus in the following manner: I bring in the subscribers' lines to one or more central points and at each of these central points I place what I call a primary selector set, whereby the lines when calling 20 are automatically connected to idle trunks which lead out from primary selectors to the connective apparatus. For a small exchange this connective apparatus is located in immediate juxtaposition to the primary selec- 25 tors. In a large exchange the primary selectors are preferably located at convenient distributing points or branch exchanges, and the trunk lines run thence to the main office or "clearing house," where the connective 30 apparatus is located.

There are two ways in which I can treat this connective apparatus. Using an exchange of 1000 lines for example, this would require, according to the usual calculation, 35 10% or 100 trunk lines, with a corresponding quantity of connective apparatus. According to the present invention I may either terminate these trunks in sets of connective switches, one set for each trunk for selecting 40 lines desired to complete a call, or I may apportion a smaller quantity of connective apparatus among the trunks and provide for a calling trunk to automatically select an idle set of connective apparatus. In 45 other words, while there may be 10% of trunks coming into the "clearing house," or leading from the primary selectors in a small exchange, there are cases where not more than 5% of actual connective apparatus is 50 required. In addition to the connective apparatus, a leading characteristic feature of the invention lies in the use of what I call secondary selectors for connecting the trunks when calling to idle operators for attention.

The operators ascertain the numbers wanted, 55 and then control the connective switches so as to produce the desired connection. This can be done in divers ways, of which I shall describe what I consider the simplest typical way herein. I shall also refer to other 60 ways, the underlying basis of all of them being that the line is automatically brought to and connected with the operator, and that the operator completes the connection by controlling further apparatus. The duties 65 of the operator are reduced to the performance of two acts only, viz., obtaining the number wanted and setting the same up on buttons resembling those of an adding machine, thereby connecting a power operated 70 transmitting machine to send the desired numbers and so operate the automatic switching apparatus.

The form of my invention which I have selected for illustration herein comprises 75 trunks having access to the lines of the exchange at both ends of the trunk, and having access to the operators of the exchange at a point midway of the trunk. The operation of the trunk is as follows: When a line 80 calls, the first end of an idle trunk automatically connects with the calling line; the trunk then automatically selects an idle operator's equipment and notifies the operator of the call; the operator then takes the subscriber's order and controls connecting apparatus at the second end of the trunk, whereby the second end of the trunk automatically connects with the desired line, thus connecting the calling with the called 90 line; last of all my system provides for the automatic release of the operator's equipment from the trunk when the called line has been picked out, and provides for the automatic release of the trunk by the subscribers when the conversation has been completed.

My invention is illustrated in the accompanying drawings wherein—

Figure 1 shows the subscribers' stations 100 and lines. Figs. 2, 3 and 4 show portions of three primary selector sets. Fig. 5 shows a set of signaling buttons and an impulse generator to work in connection with Fig. 6. Fig. 6 shows a trunk circuit with a secondary 105 set of relays which are normally disconnected from it. Fig. 7 shows automatic switch circuits. Fig. 8 is a modification of Fig. 6

and works in conjunction with Fig. 7. Fig. 9 shows apparatus equivalent to that of Fig. 5 but adapted to operate in connection with Figs. 8 and 7. In this figure the toothed number wheels are driven from a power shaft and the connection between the wheels and the shaft is made by a mechanically controlled clutch. Fig. 10 is a condensed diagram of a primary selector set. Figs. 11 and 12 are respectively a side and top plan view of a ten point relay used in my system. Fig. 13 is a plan view showing a strip of keys or buttons containing two signal lamps. Fig. 14 is a plan view showing the slide which controls or latches the various buttons. Fig. 15 is a sectional view of a portion of one of the strips of buttons. Fig. 16 is an end view showing the buttons mounted on an inclined support or cabinet. Fig. 17 is a plan view showing a strip of ten buttons. Fig. 18 is a top plan view of Fig. 16 showing the arrangement of the various sets of buttons, there being one of these outfits for each operator. Fig. 19 is a diagram showing switches instead of relays for primary and secondary selector sets. Fig. 20 is a skeleton diagram showing a number of subscribers' stations, a central office equipment having primary and secondary selectors only, each secondary selector being appropriated to one operator's key set, subscribers' lines being shown multiplied into both the primary selectors and the outgoing or selective automatic switches. Fig. 21 reproduces a portion of the trunk 30-31 of Fig. 6 and shows also the corresponding portions of trunks 130-131 and 230-231, to illustrate the relation existing between the trunks, whereby one trunk always is held in readiness to respond to a call instituted by a telephone line. Fig. 22 reproduces the secondary selector equipment of Fig. 6 in duplicate, showing the relation between the operators' equipments and the trunk circuits whereby an active trunk will select and connect with an idle operator's equipment.

Before proceeding to the circuits, wherein the invention in the present case resides, it will be advisable to obtain a clear understanding of the types of apparatus which I employ, and which are shown in Figs. 9 to 18 inclusive. I do not give any special illustration of a single point or ordinary relay, for the reason that everyone skilled in the art is so familiar with these devices as to render it unnecessary. That portion of my system which is illustrated in Figs. 2, 3 and 4 constitutes what I have termed the primary selector or answering portion of the system. In this, as already set forth, appear a number of ten point relays and a number of single point or ordinary relays. These latter may be of any suitable type. The only special feature required is that of double winding, which, as I shall point out

hereinafter, can be dispensed with if some other means be provided for locking the relays when energized.

The apparatus at the subscribers' stations also forms no part in itself of my present invention, except as it co-acts with the apparatus and circuits at the central office. I contemplate using an ordinary common battery telephone outfit the same as those employed in standard manual switchboard systems.

Referring then to Figs. 11 and 12, I will briefly describe the ten point relay N. This comprises an iron back yoke n, a pair of magnets n' mounted thereon, an armature n² extending across the front end thereof, and a set of contact springs n³, n⁴, n⁵, n⁶, overlying the upper bell crank extension of the armature, so as to be worked thereby. There are eleven sets of these springs, all secured at the rear end of the relay upon the return member n⁷, of the back yoke. The front ends or pole pieces of the cores of the electromagnets n' receive the front yoke n⁸ of non-magnetic material, such as brass, this also having an upper return portion n⁹ overlying the magnet windings, and aligned with the return portion, n⁷, of the back yoke n. Upon this return portion n⁹ of the front yoke the upper bell-crank arm n¹⁰ of the armature n², lies flat under normal conditions. Cut from end to end of this upper bell-crank portion n¹⁰ are two grooves in which rest the insulating studs of the spring sets. The function of these slots with the studs resting in them is to retain the armature in place. At their front ends the springs are separated by shouldered studs, the lowermost stud of each pair resting upon the armature, carrying the lower spring of its pair n³ on its shoulder, and the upper spring n⁴ on its head, its stem passing through a hole in the spring, n³, while the uppermost stud of each pair rests upon the spring n⁵, supports the spring n⁴ upon its shoulder, and carries the spring, n⁶, on its head, its stem passing through a hole in the spring n⁵. The actuating studs affect only the springs n³, n⁵ of each set, these constituting the movable springs, while the others n⁴, n⁶ are fixed. Each actuating stud carries the spring n³ on its shoulder, and the spring n⁵ on its head, its stem passing through holes in the springs n³, n⁵. The entire relay is secured to an insulating back block, n¹¹, by means of the bolts n¹², constituting extensions of the cores and threaded to receive lock-nuts. The rear ends of the contact springs extend out through openings made in this block, and an inclosing shell or casing n¹³ is fitted to the block, with which it forms a tight joint all around the edge. This shell is secured in place by means of the stud n¹⁴ threaded to receive the nuts n¹⁵.

As the armature n^2 is attracted, the springs n^4 , n^6 are lifted by the actuating stud, until their outer points make contact with the corresponding points of the springs 5 n^3 , n^5 in each set. Ten of these sets are line contacts, and the eleventh is for locking purposes, as will sufficiently appear from the description of the circuits.

The same structure of relay frame is used 10 for these relays as for those relays in the primary selector wherein it is desired to break a number of circuits, as for instance in the relay Dx of Fig. 6. In such an instance, the shoulder studs are cut to support springs 15 n^4 , n^6 and the actuating studs are adapted to lift springs n^3 , n^5 away from springs n^4 , n^6 respectively.

The switches which I preferably employ herein, and which are referred to in the pre- 20 amble as connective apparatus, may conveniently be the standard Strowger automatic switches, such as shown in the patents to Keith & Erickson, No. 815,176 and No. 815,321, dated March 13, 1906. No further 25 description of these switches is necessary therefore. Any specific differences between the present specifications and those of the patents referred to will sufficiently appear from the statement of operation.

30 The next piece of apparatus requiring attention is the operator's impulse transmitter or key set, which is shown in Figs. 13 to 18, inclusive. Referring to Figs. 13, 14, 15 and 17, the construction of these key sets is very 35 plainly shown. The contact springs 73, 79, and the lamp jack springs k^9 and k^{10} are mounted in a rubber block k^{21} which is attached rigidly to the plate k^{12} by means of the screws k^{11} passing through a clamping 40 strip k^7 and screwed into the plate k^{12} . The two strips k^8 and k^2 are also rigidly fastened to this plate by means of small screws or rivets. These two strips are provided with the ribs k^{13} which form the bearing 45 for the slide k' . This slide is provided with clearance holes k^{15} , plainly shown in Fig. 14. The slide is kept in its normal position toward the left by the tension spring k^{14} which is mounted in a manner similar to that of 50 the contact springs. The strips k^3 and k^2 are also provided with openings which lie directly in line with those of the slide k' . These holes or openings are fitted with the buttons K which consist each of the rubber 55 plunger head k which is fastened to the rod k^{40} . This rod contains the metal cone k^6 which can be a separate piece or a portion of the rod k^{40} . The heads of the buttons k^{30} are attached to the rod in the same manner 60 as the plunger ends and are kept in a locked position by means of the lock nut k^5 . Referring to Fig. 15, when one of these buttons is depressed the cone k^6 passes through the opening in the slide k' , and the slide under tension of the spring k^{14} is caused to

ride over and hold the cone in its downward position. The button is kept in this indicating or locked position until some other button in the same strip is depressed. The button is then released as soon as the edge of the 70 cone of the button which is being depressed enters the opening in the slide k' . The buttons are forced up or returned to their normal position by means of the contact springs 790 riding on the cone portion of the rubber 75 plunger. When a button is depressed the contact springs 73 and 790 are connected. Referring to Fig. 13 the listening button K^* when depressed closes the contacts of two sets of springs so as to enable the operator 80 to bridge her talking set across the trunk. This button, as well as that of the starting button K^{*1} is not provided with the cone k^6 , as they are not to be kept in a locked position or restore any of the buttons in the set. 85 The lamps L and L' are separated by a strip k^8 so as to prevent the lighting of one causing the bull's-eye of the other to be illuminated. Referring to Fig. 17, I have shown a full strip of ten buttons, the operation and construction of which is the same as that of the four buttons shown in Fig. 13. All of the buttons in Fig. 17 are arranged so as to release one another.

Referring now to Figs. 16 and 18, I have 90 shown the arrangement of the buttons for one operator's position where the capacity of the exchange is ten thousand lines and where provision is made for 4-party selective ringing. Referring to Fig. 18, the first row of 100 buttons K' represents the thousands digit; the second row K^2 , the hundreds digit; the third row K^3 , the tens digit; the fourth row K^4 , the units digit; the fifth row K^5 contains the four selective ringing buttons, the two 105 signal lamps, and a listening and a starting button. The operator is provided with three of these sets as shown. If the first set is busy the next idle set will come in use and so on. To distinguish the various sets 110 and form dividing lines I use different colored buttons; for instance, the buttons of the first row are white, the second black, the third white, the fourth black, and the fifth red. The cabinet or frame k^{20} on which 115 these keys are mounted is of pressed metal and in appearance greatly resembles an adding machine. These cabinets can be mounted on iron frames similar to the stands of adding machines and can be placed in any position desirable, or, the cabinet can be mounted on a typewriter table and be placed under cover when the operator leaves. In fact these stands or cabinets can be placed in any position desirable, which shows the 120 flexibility of my system.

A very important feature of this invention lies in the provision of a common impulse generator or commutator, and individual selector wheels having teeth of differ- 125 130

ent lengths, these teeth being so proportioned, and the wheels so run relatively to the main commutator, that they will always make and break a little before and a little after the commutator circuit is made and broken, respectively, which positively avoids sparking at the contact pens. This arrangement is diagrammatically shown in Fig. 5, wherein I have illustrated the main 5 commutator, one set of number wheels, an electric motor for driving the shaft common to all of these, and a set of operator's buttons similar to those shown in Figs. 13 to 18. Fig. 9 shows the same elements with 10 the exception of the electric motor, which is therein replaced by an electromagnet controlling a clutch which throws power on and off from a constantly driven shaft. This is the preferred arrangement. 15 Attention is called to the details of the clutch $x^{20}-x^{20}$ of Fig. 9. x^{20} is a toothed member and x^{20} is a member having a single tooth. By this arrangement a definite angular relation will be obtained between the 20 driving shaft of x^{20} and the driven shaft of x^{20} , hence between the teeth of the commutator wheel Q^{10} and the teeth of the toothed impulse wheels Q' , Q^2 , Q^3 , etc., whereby wheels Q' , Q^2 , etc., may always break circuit with their pens in an interval of open 25 circuit at the commutator Q^{10} .

Figs. 5 and 9 show what I shall call a multiple number transmitter having a common impulse generator for the entire 30 change and individual selector wheels. In Fig. 5 I have shown these individual wheels being driven by a motor which starts up when the operator depresses the starting button. Fig. 9 shows the individual wheels 35 being operated by a magnetically controlled clutch which when operated by the operator pressing the starting button, connects them to a constantly rotating shaft. The wheels Q' , Q^2 , Q^3 , Q^4 , are provided with 40 teeth of different length. The tooth on wheel Q' being the shortest, while that of Q^4 is the longest, the tooth of the wheel Q' in passing over a contact pen transmits one 45 impulse through the medium of the common commutator Q^{10} . The tooth of the wheel Q^4 in passing over one of these pens transmits five impulses through the same medium. A complete machine will have ten 50 of these wheels so that any digit from one to ten can be indicated by sending the appropriate number of impulses. In the drawing, in order to economize space I show only the first five wheels. In practice, these 55 wheels are all one, the teeth being formed upon the surface of a drum which is driven by a suitable motor or shaft. The speed which I have found most suitable for this device and for the type of switches I here 60 illustrate is approximately twelve revolutions per minute. For a one hundred line ex-

change which I am illustrating the first four wheels will be provided with three pens and the remaining six provided with two pens each. These pens through which the impulses are transmitted are connected in their proper order to the buttons of the sets K' , K^2 and K^3 . Thus the pen q is connected through wire 74 to the individual spring of the first key in the set K' , the pen q' of the 70 com. Q' is similarly connected through the wire 75 to the second key of the set, and so on for all the pens of the first set. The second set of pens q^2 are similarly connected in order to the individual keys of the set K^2 , and the third set of pens q^3 are similarly 75 connected to the keys of the set K^3 . The layout in the drawings is intended for an exchange of one hundred lines or less, the two sets of keys K' and K^2 serving to control two sets of number wheels for line selection purposes while the third set of keys K^3 is intended in the present case for selective ringing on party lines. 80

The wheel Q containing the three teeth transmits what is commonly called the rotary impulse to affect the side switch mechanism in the connector switch. The impulses from this wheel instead of being controlled by battery through the medium of the commutator Q^{10} send grounded impulses operated directly by the teeth coming in contact with a single pen. The wheel Q^{25} has an insulated point upon which the contact spring q^6 normally rests. After this wheel is started by the operation of the motor or clutch, the pen q^6 riding on the metal portion of the wheel maintains a closed circuit for the motor which will continue to run until the wheel Q^{25} has made one complete revolution and the pen q^6 again rests on the 90 insulated portion. The controlling circuit may be traced as follows: battery B, Q^{25} , q^6 , wire 82 (passing from Fig. 5 to Fig. 6) to relay H and ground. The relay H is pulled up as soon as the starting key is pressed, this starting key K^7 merely putting battery on to the relay in parallel with the wheel Q^{25} . The relay H closes the following circuit: battery B (Fig. 6), wire 29, armature h , wire h' , to relay H' and ground. Relay H' 95 therefore remains energized as long as relay H holds up, and the motor circuit is maintained closed by the following path: (in Fig. 6) from the dynamo or motor supply battery, or the main feeder circuit thereof, by wire 47 to armature h^a , h^b , wire 83, into Fig. 5 and to the motor, then returning by wire 86 into Fig. 6, and thence back to the dynamo or battery. The teeth on the wheel Q are so set that they come successively in contact with its pen immediately after the teeth of the impulse wheels have ceased sending their respective impulses, so that a complete signal will consist of (1) a set of number digits; (2) a rotary impulse; (3) 100

another set of number impulses; (4) another rotary impulse; (5) a third set of number impulses; and (6) a final rotary impulse.

The common springs 790 of the key set 5 with the exception of the spring 790 of the button K' are connected together to a common wire 79. This common wire carries the actuating impulses to the switches in proper sequence.

16 To illustrate clearly the operation of this device, suppose it be desired to transmit over the wire 79 the number 43-3. The operator depresses the fourth key in the first set and the third key in the second set, and 15 finally the third key in the third set. Thus the spring q^1 of the wheel Q^1 becomes connected to the wire 79; the spring q^2 of the wheel Q^2 becomes connected through its wire to the wire 79, and the spring q^3 of the wheel Q^3 becomes connected through its wire and number key to the common wire 79. Now as the drum or wheels rotate what happens is this: First, four impulses from the wheel Q^1 ; then 25 a single impulse from the wheel Q^2 ; then three impulses from the wheel Q^3 ; then one impulse from the wheel Q^1 ; then three impulses from the wheel Q^2 , and finally a single impulse from the wheel Q^3 , so completing 30 the signal. Anyone familiar with the Strowger system of switches will at once perceive that the wires 79 and 84 (these being respectively the vertical and the rotary impulse wires) can be connected directly to 35 or so as to repeat into the vertical and the rotary side of a switch trunk, respectively, and the impulses will then serve to operate the switches perfectly. I may here state that the sole function of the wheel Q^2 with 40 its wiper q^2 is to send in one complete set of impulses and then stop. Obviously, if the operator sets up the signal keys and the impulses were permitted to go directly into the switch circuits without any starting 45 point, great confusion would result. For this reason I have the various signal wheels always come to rest at a normal starting point which is controlled directly by the wheel Q^3 and the pen q^3 . The circuits of 50 Fig. 5 thus described are particularly adapted to cooperate with the trunk circuit shown in Fig. 6.

Having thus described the mechanical parts, attention is invited to Fig. 20, which 55 shows the general plan or layout of the circuits. This figure contains no reference letters, but is inscribed with suitable legends instead. The subscribers' stations are shown connected to the central office by line wires 60 which are multiplied into the primary selectors (which may be either relay sets as shown in Figs. 2 to 4 inclusive, or switches as shown in Fig. 19), and each primary selector talking trunk passes to a terminal 65 selector switch through which access may

be gained to wanted subscribers. In order to gain access to more than one hundred lines, it is necessary to provide additional groups of switches, such as "second selectors", "connectors", etc., but as the use 70 of such supplemental groups is perfectly well known in the art, I have merely indicated all of the selective switching apparatus in Fig. 21 by the outline of a square in each case. This selective switching apparatus 75 contains multiple contacts of the subscribers' lines, which for convenience are shown as of the same group which are multiplied to the particular primary selectors also shown in the figure. To control the selective switches, 80 operators' key sets are provided, each connected to a secondary selector set (which may be either of the relay type shown in Fig. 6 or of the switch type shown in Fig. 19), and multiple taps are taken off from the 85 talking trunks and carried into these secondary selectors.

When one of the subscribers calls, current in his line causes the actuation of an idle primary selector whereby he becomes 90 connected to an idle talking trunk and its terminal selective switch or switches. The trunk being thus put in commission, has produced within it circuit changes which cause an idle secondary selector to pick it 95 up and connect it to the corresponding idle operator's key set. There may be several of these key sets for each operator, and in fact all three key sets shown in the figure may be located in front of a single operator if desired. The number of operators and the number of key sets provided is of course determined by the traffic conditions depending on the number of lines to be served, and the extent of their use. The operator receiving 100 the number orally, sets up her keys and thereby permits a corresponding number of impulses to pass over the talking trunk to the selective switches, which are thereby actuated to connect the trunk with the wanted 105 line. The secondary selector then becomes automatically disconnected, the operations of testing, ringing, and finally disconnecting the lines being mechanically performed and entirely independent of the operator. 110

Having thus described the mechanical parts a knowledge of which is essential to the comprehension of my circuits, I turn to the description of the latter, beginning with 120 Fig. 1. Therein I have shown three subscribers' stations, A, A', A'', each equipped with a telephone transmitter, a receiver, a switch-hook, a ringer, and condenser, all of usual or suitable type for use with common battery circuits. When the hook is 125 up, that is, when it is relieved of the weight of the receiver, the circuit is through the transmitter and receiver; and when the hook is down, the line circuit is completed for 130 alternating current only, through the ringer

and condenser. Since the circuits are the same for all the lines, I will refer to the line from station A² only. This consists of conductors 1 and 2, extending from the substation to the central office. At the substation the talking circuit is completed through the wires 3-4 when the hook is up, and the ringing circuit through the wires 5-6 when the hook is down. These figures are useful for the purpose of tracing the circuits only.

Turning to Fig. 2, the line wires 1 and 2 appear at the left-hand side of the figure terminating in contacts of the cut-off relay, M', which is normally deenergized, so that in each case the line wire 2 is grounded at 7 and the line wire 1 extended through wire 8 to the line relay M, and so to main battery B and ground. The armature m, of each line relay M is grounded at 9, and when attracted is adapted to close upon terminal contacts of wires leading to the tens and units relays of the primary selector sets. I preferably divide all the incoming lines in an exchange into groups of say one hundred each, and to each group I apportion a fixed number of trunks leading to connective apparatus. In a small or comparatively inactive exchange the percentage of these trunks may be as low as five, and in busy exchanges it may be raised to ten or even fifteen. I assume, however, that ten per cent. of connective apparatus will be sufficient to care for the present system, hence I provide ten trunks for each one hundred lines, and a complete set of tens and units relays in a primary selector group for each trunk. The circuits herein illustrated show six lines, which for convenience I will call Nos. 500, 501 and 502 (Fig. 2) and 510, 511 and 512 (Fig. 3). The subscribers' circuits of Fig. 1 will fit any of these, and in order to fully comprehend the connection of these lines and the arrangement of the tens and units relays, it is necessary to consider Figs. 2, 3 and 4 together.

In Figs. 2 and 3 the subscribers' extension lines are shown coming into their initial terminals on the tens relays, which are of the type shown in Figs. 11 and 12. Each of these relays carries the terminals of ten lines, and for each trunk there are ten of these relays, so that for 100 lines, provided with ten trunks, there will be 100 ten point relays, containing 1,000 line terminals; from which it appears that each line can be multiplied ten times, which it should be in order to obtain access on occasion to every one of the ten trunks. The contacts on the ten point relays are arranged in duplicate pairs. That is, the incoming lines terminate each on one pair of springs, opposite which another pair of springs appears to which the line is connected when the relay is energized, and from which a local circuit passes to the

front contact springs of a particular units relay or single point relay. For each group of ten tens relays there are ten units relays, or twenty relays in all for each trunk. A group of this kind constituting one primary selector trunk terminal for thirty lines, is shown in Fig. 10 apart from the other figures, so as to free the lines from their multiple connections. In order to make clear the connection of a line coming into the exchange, I will first refer to this figure and then trace the circuits through the others.

In Fig. 10, N, N', N², are three relays of the type shown in Figs. 11 and 12, having ten pairs of contacts each for the line circuits. These relays correspond to the relays shown in Figs. 2 and 3, correspondingly lettered. At the top of the figure, I have shown the terminal ends of lines 500 to 529, inclusive, connected to a pair of contacts, n³, n⁵, such as shown in the mechanical figures 11 and 12. For lines 500 to 509 these terminals are in the relay N. For lines 510 to 519 they are in the relay N'. For lines 520 to 529 they are in the relay N². Thus each relay contains line terminals, n³, n⁵, for ten lines. When any one of the lines appropriated to a particular relay is calling, the electromagnet n', of that relay becomes energized. This will be explained in connection with the circuits of Figs. 1 and 2 farther on. For example, if any line from 500 to 509 originates a call, the magnet, n', of the relay N, will become energized, and simultaneously connect all of the lines from 500 to 509 onto the extensions 10' to 19' inclusive. If, however, the calling line is in the group from 510 to 519, the magnet, n' of the relay N' will become energized, connecting all that group onto the extensions 10' to 19' inclusive. Similarly, if the calling line be in the third group, from 520 to 529, the magnet n' of the relay N² will be energized, connecting that entire group onto the extensions 10' to 19' inclusive. Thus extensions 10 to 19 are seen to be common to all of the tens relays, and in fact each extension pair is multiplied to corresponding contacts in all of the tens relays. No. 10' extension goes to the first pair of contacts n⁴, n⁶ in each of the relays N, N', N². Extension No. 11' is multiplied to the second pair of contacts n⁴, n⁶, in each of the relays, and so on with all the extensions up to No. 19'.

At the lower edge of Fig. 10 I have shown ten units relays, marked P to P⁰ inclusive. These are the same as the relays in Fig. 4, similarly marked. Each is a simple standard relay of the type in common use, and preferably of the same general type as that shown in Figs. 11 and 12 hereof, viz., that type in which the electromagnet is mounted horizontally on a frame or rack, carrying the contact springs upon it, and the whole is inclosed within a dust-proof shell. Each

relay has an armature p^2 , adapted to be actuated by an electromagnet p' , to close together the contacts p^3 , p^4 , and p^5 , p^6 . In the present instance, that is in the trunk group 5 of each primary selector, all of the contacts p^5 of the entire set of relays P to P^6 are connected together, forming a set of double parallel branches marked 20 to 29 inclusive, which are really so many bridges across the 10 trunk circuit 30-31.

The outfit shown in Fig. 10 is sufficient for 30 lines, and by its use any one of the lines 500 to 529 may connect itself to the trunk 30-31, by merely closing its line circuit, and energizing the appropriate tens and units relays. The energizing circuits are not shown in Fig. 10, but will be described in connection with Figs. 2, 3 and 4. They comprise parallel branches closed by 20 the line relay of each line when calling, one branch going to the appropriate tens relay, and the other branch going to the appropriate units relay, which thus become energized simultaneously and act in conjunction 25 to connect that particular line and no other to the trunk. For example, suppose line No. 512 is calling, the subscriber having taken his receiver from the hook so as to close his line circuit as shown in Fig. 1, and energize 30 his line relay M shown in Fig. 3. This line relay closes two branches, one leading to the tens relay N' in Fig. 10, and the other leading to the units relay P^2 , which is the third in the set of ten. The actuation of the tens 35 relay N' connects all of the lines 510 to 519 onto the extensions 10 to 19 inclusive; but it will be observed that these extensions are open everywhere else, hence no effect is produced by this action alone. The third units 40 relay P^2 , however, connects the third extension 12 to the trunk 30-31, through the branch 22, and by the following circuits in Fig. 10 it will be found that this connects the line 512 onto the trunk direct, whereupon 45 other trunk relays become energized, and further proceedings may be had. Only one line is thus connected to the trunk at a time, assuring of course that only one tens relay and one units relay of the same set be energized simultaneously. It is true that the 50 tens relay connects all of its lines onto the extensions; but all of these extensions are open except the particular one which is closed onto the trunk by the particular units 55 relay energized. It is also true that the extension thus connected to the trunk is multiplied to the corresponding pair of contacts in every one of the tens relays, but this produces no effect, because all but one of the 60 tens relays remain deenergized.

Before passing from Fig. 10 it is necessary to call attention to the fact that only three tens relays are there shown, accommodating thirty lines. This limitation is due to the 65 necessary limitation of a patent Office draw-

ing, and it is to be understood that the same principles apply to any desired group up to 100 or more. It is most convenient in a scheme like this to make use of the decimal system, using ten relays per trunk, ten lines 70 per relay, and ten trunk multiples per line. For 100 lines there would be ten of the tens relays, N , N' , N^2 , etc., but still only ten of the units relays, and each of the extensions 10' to 19' inclusive instead of being multiplied three times, would be multiplied ten times, onto all the tens relays. 75

Turning to Figs. 2, 3 and 4 we have the same relays described in connection with Fig. 10 but somewhat differently arranged. Only two tens relays and three units relays of each set or of each trunk are shown. I have assumed the numbers 500, 501 and 502 for the lines entering Fig. 2, and 510, 511 and 512 for the lines entering Fig. 3. The first three lines being within the same tens digits with each other go onto the same tens relays in each set. For the sake of convenience I have given the designating numerals of the relays coefficients. Thus in Fig. 2 all three of the lines come into the relay N , which is adapted to put them onto the extensions 10', 11', 12', etc., leading to the units relays P , P' , P^2 , etc., in Fig. 4. (I should here remark that the tens relays in 80 Figs. 2 and 3 are not shown with their full complements of springs, for the sake of simplicity. Each of them is supposed to have ten pairs of contacts, in accordance with the showing of Figs. 11 and 12.) Each of the lines 500, 501 and 502 not only terminates in contacts of the relay N , but is multiplied to similar contacts in the relays $1N$, $2N$, etc., pertaining to additional trunks serving the same lines. There would be one of these 85 added for each trunk, that is appropriated to the group of lines. In the present case I only illustrate three trunks, so that each line would be multiplied only three times. In Fig. 3, the lines 510, 511 and 512 are connected to the tens relays N' , $1N'$, $2N'$, in the same manner as the lines in Fig. 2, each being multiplied three times so that each may have access to any one of the three trunks. It will be understood of course that the relays N , N' , of Figs. 2 and 3 and P , P' , P^2 of Fig. 4, constitute one set, appropriated to the trunk 30-31, and have precisely the same relation among themselves and the same connections as the set shown in Fig. 10. Similarly the relays $1N$, $1N'$, $1P$, $1P'$, and $1P^2$ all belong to one set, appropriated to the trunk line 130-131. Similarly again, the relays $2N$, $2N'$, $2P$, $2P'$ and $2P^2$ belong to one set, appropriated to the trunk line 135 130-131. The extensions from the tens relays to the units are marked 10', 11' and 12' for the first set, 110, 111, and 112 for the second set, and 210, 211 and 212 for the third set. As these of course bear a logical 140 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

relation throughout, and follow the same arrangement as that in Fig. 10, it is thought no difficulty will be experienced in comprehending the meaning of Figs. 2, 3 and 4. 5 If Fig. 10 is understood, the description of the other figures may be put into one sentence. They show several groups like Fig. 10, with the line wires multiplied to each group instead of terminating as in Fig. 10 10 in single pairs of contacts.

The actual connections controlled by the relays N and P being thus understood, it is most important to explain the means by which I control these relays. Referring 15 to Fig. 2, the line wires 1 and 2 terminate as I have stated, in the contacts of the cut-off relay M', through which they are normally connected to the line relay M and ground respectively. When the sub- 20 scribe at station A² takes the telephone from the hook, he closes his line circuit, the line relay M is energized, and the two branch circuits 50 and 51, are immediately closed. The branch 50 passes in multiple 25 to one winding of each of the three tens relays N, 1N and 2N, these relays being double wound for the purpose of making them self locking when attracted. Any one of these relays might thus be energized by 30 any one of the three lines shown, but it is shown later herein that only one of them may be so energized at once, and that no two lines shall be able to energize the same relay at the same time.

35 Referring to Fig. 6 the arrangement of this trunk 30-31 is as follows: To the incoming end of the trunk wires 30 and 31 are connected the relays D and D' respectively. The relay D is normally disconnected from ground through the relay D'. The relay D' becoming energized in series 40 with the line cut-off relay through the talking contacts of the primary selector relays, attracts its armatures and connects ground to the relay D, thus furnishing a circuit for talking current to the calling subscriber. The relay D' also controls the circuit of the relay D^x which becoming energized opens the circuits leading to the 45 actuating windings of the various relays in the primary selector set, thereby preventing any relay of the primary selector of the trunk 30-31 from responding to any subsequently calling line so long as the 50 relays D' and D^x remain energized. The particular primary relays which have already responded to the calling line, however, remain energized because of the formation of separate locking circuits 55 controlled through the wire 57. Let us assume that subscriber A² has called in Fig. 1, that his line relay M has pulled up, and that the primary relays N and P² have pulled up, these two relays corresponding 60 to the number of that line and adapted to

connect it to the trunk 30-31. The relay N immediately forms a locking circuit for itself as follows: from battery B in Fig. 6 through 28, 17, 14, 57 (into Fig. 4), 61, secondary winding P², locking contact and ground back to battery. The locking wire 14 in Fig. 6 is common to the locking windings of all the primary relays associated with the trunk 30-31. It is controlled first by the relay E which is normally de- 65 energized, and second by the relay D which pulls up and remains energized during conversation. The contacts e², e³ are provided merely in order to insure the normal connection of battery to this wire before the 70 relay D has responded to the call. The moment the trunk becomes connected through these relay contacts with the line, current flows from the battery in Fig. 6 through the sleeve relay of D' and through 75 the trunk wire 31 to the line sleeve extension and the cut-off relay M', which immediately snaps its armatures down so as to connect the line wires 1-2 onto the extensions whereupon the battery current 80 through trunk wire 31 will also flow out to line and back through the trunk wire 30 to the tip relay D which will thereupon pull up. The method of energizing the 85 relay E will presently appear and it is 90 sufficient to say here that as soon as the tip relay D responds, it takes control of the connection and thereafter the subscriber A² holds the same subject to his own will. When he hangs up the relay D 95 lets go and permits the primary relays to 100 clear out and release the line by breaking the locking circuit aforesaid.

The relation existing between the several trunks of the same group whereby one idle 105 trunk of that group always stands ready to respond to a calling line is illustrated in Fig. 21. Here the trunk 30-31 stands normally ready to respond to the first call 110 in its group of lines, by reason of the closed contacts of its relay D^x, through which the battery wire 28 is normally connected to wires 54, and thence through the actuating windings of the primary relays of the 115 trunk, to the line relay contacts whereby the operation of any line relay will cause the proper primary relays to pull up. The primary relays of other trunks, however, will not be energized as long as trunk 30-31 is idle, because their respective wires 120 54 are disconnected from battery through the contacts of relays 1D^x, 2D^x, etc. When the relay D' pulls up in the first trunk, after a call has landed on that trunk, the contact d⁷ puts current on its own associated relay D^x and through wire 600 to the relay 1D^x of the next trunk. The relay 1D' of that trunk when it comes into 125 service cuts off battery from its own relay 1D^x and puts it onto the corresponding re- 130

lay $2D^x$ of the next trunk, and so on. If this arrangement is made use of the relays subsequent to the first one must have their contacts normally opened, since they are successively energized instead of de-energized to put the trunks into commission. I prefer the arrangement of Fig. 21 since this involves the merest duplication of what is shown in Fig. 6.

10 The function of the primary relays of my system is to connect an idle trunk with a calling line. The call upon the line at first energizes the line relay M and extends no farther into the system. In response to the 15 call a trunk connects with the line. The call now extends into the central office system as far as the trunk, and as the call is not yet satisfied the trunk in this condition may be referred to as a calling trunk. In 20 a calling trunk the relay D' is energized as the relay M is energized in a calling line.

I provide operators' equipments as shown in the lower portion of Fig. 6, which are connected with conductors constituting substantially secondary trunks. The secondary trunk or operator's equipment is adapted to respond to a call upon a main trunk in a manner analogous to the response of a main trunk to a call upon a subscriber's line. In 30 this analogy relay D' of the main trunk corresponds to relay M of this line; relay F of the secondary trunk corresponds to the tens relay N or N' of the main trunk; relay F' corresponds to the units relay P or P' of the main trunk; relay F^2 corresponds to relay D^x of the main trunk; relay T of the secondary trunk corresponds to relay D' of the main trunk in that it controls the energization of relay F^2 and in that it controls 40 the signal lamp L which calls for the response of an operator just as relay D' calls for the response of a secondary trunk or as relay M calls for the response of a main trunk. A relation or condition of 45 precedence among secondary trunks exists which parallels the condition just described above existing among main trunks. This arrangement in the secondary trunks is shown in Fig. 22. In this figure the lower 50 trunk has closed contact upon relay F^2 while the upper trunk has open contacts upon relay $4F^2$ whereby the potential of battery B is passed through the contacts of relay F^2 to the actuating windings of the 55 relays F or F' of the operator's set of which the listening key K^x is a part, the path from battery B thence extending over wires 18 and 118 upward out of Fig. 22 and into Fig. 21, thence through back contacts on relay E to contacts at armature d^x of relay D' , to ground and back to battery.

The secondary tens relay F is that relay of the operator's set which contains multiple terminals of that group of ten trunks 60 of which trunk 30-31 is one; the units

relay F' is that relay which contains a pair of terminals corresponding to the units digit of the trunk 30-31 in the group, counting from 0 to 9, or from 1 to 0. An additional operator's set, of which the listening key $4K^x$ is a part, has similar tens and units relays $4F$ and $4F'$. It is understood of course that each secondary trunk has its full equipment of a plurality of tens relays and a plurality of units relays for answering calls upon main trunks just as each main trunk has a plurality of relays of each class for answering calls upon lines. The main trunks are multiplied into contacts of relays F, $4F$, etc., as lines are multiplied into relays N, N' , etc.; the secondary trunks, viz. wires 39-40, are multiplied into all the primary relays of each secondary set of relays just as the talking conductors 70 75 80 85 90 95 100 105 110 115 120 125 130 30-31 of any main trunk are multiplied into all the units relays of the primary selector set pertaining to that main trunk. By the actuation of a tens and a units relay of a secondary set, the secondary trunk 30-40 is connected to the main trunk 30-31. This results in energization of the relay T over the following path: battery B, of Fig. 22, wires 28-29, 42, armature h^x , contact h^{1x} , wires 41, 38, 36, 43, winding of relay T, contacts t^x , t' , wire 44, contact h^2 , armature h^2 , wire 40, contacts of relay F^2 , wire 35 (see Fig. 6), contacts of relay F, wire 32 and winding of relay S to ground. In response to this current relay T is energized and locks itself to earth by connection of armature t with contact of t^x . By its armature t^x it closes path for current from battery B over 28, 29, t^x , t' , F^2 to earth, breaking contacts of F^2 whereby all actuating windings of the secondary set of relays are operated; also over path B, 28, 29, t^x , t' , 602, $4t^x$ and winding of relay $4F^2$ to earth, energizing relay $4F^2$ which through its contacts passes potential of battery B to the actuating windings of all relays of the secondary set pertaining to the secondary trunk 639-640. Thus secondary trunk 39-40 may not respond to further calls until after having been released and secondary trunk 639-640 will respond to the next succeeding call.

It should be understood that the relation between the trunks involves mere duplication, and therefore I may duplicate the relays T and F^2 in the same relation in each secondary trunk, simply cutting battery from one to the other in a well known manner. This idea as applied to the main trunks and their primary selectors is illustrated in Fig. 21, so that further illustration would seem unnecessary. The particular arrangement of the armatures of the relays T, F^2 or D^x (Figs. 6, 21, and 22) is non-essential, so long as the desired function is performed, to cut off the primary

and secondary relays of the trunks that are out of commission, so that only one trunk at a time, either primary or secondary, will be active to receive calls.

- 5 The relay E of the main trunk is the starting relay and becomes energized only when the calling main trunk is responded to by the secondary trunk. One of its functions is to annul the calling condition of 10 the calling trunk, which it does by opening wires 18 and 118 at its armatures e'. The secondary sets of relays are only connected to the talking trunk for a short period; that is to say, until the operator has 15 received the number wanted and set up the impulse keys, thus transmitting impulses to the switching mechanism attached to the outgoing end of the talking trunk. The relays S and S' respond to the impulses from 20 the sending machine and repeat the impulses to the outgoing end of the trunk and at the same time open the incoming end of the trunk preventing the calling subscriber from receiving annoying clicks. The relay H is 25 controlled by the starting button K¹¹ shown in Fig. 5. The operation of the relay H closes the circuit of the relay H' which in turn connects battery for suitable current to the motor, Fig. 5, thus causing the impulse wheels to rotate. When the relay T 30 becomes energized it causes the lamp L to glow thus notifying the operator that a party is calling. She thereupon depresses the listening button K² which connects her 35 talking set, which is connected to the wires 49 and 50, to the wires 32 and 33 through the relays F and F'. The relay S is connected to ground while the relay S' is connected to battery and as soon as the operator 40 bridges her telephone set across these wires these two relays become energized and connect her talking set across the trunk wires and at the same time supply her with battery for talking. These two relays in drawing 45 up their armatures also perform a very useful function of placing battery simultaneously on both sides of the trunk wires leading to the switching mechanism. If any of these switches by chance were left in an operated position they would at once be restored to their normal position. The relay H while being first controlled by the starting button K¹¹ is held energized as it is 50 connected to the pen q⁶ and when this pen rests on the metal wheel Q²⁶ the relay is held energized until one complete revolution has been made. After one complete revolution this relay drops back and momentarily opens the locking circuit of the relays F and F', 55 thus disconnecting the secondary outfit from the talking trunk and leaving it in condition for another incoming call. The locking circuit of the relays F and F' is controlled by the normally open contact h⁵ of the relay H and the normally closed contact h⁹ of the

relay H' and it of course follows that if a condition be brought about such that the relay H' is energized while the relay H is de-energized, then this locking circuit would be opened for an instant. The locking circuit of the relay T is in multiple with that of the relays F and F' and it of course follows that it is affected in the same manner. When the relay H' becomes energized the guard lamp L' glows and will continue to 70 glow until the entire number has been sent, thus notifying the operator that the number is being transmitted. The circuits will be traced in detail when I describe the operation of my system. After the talking 75 trunk is connected to a secondary selector set the relay S becoming energized on account of being placed in series with the relay T for a short time, attracts its armature and closes the circuit of the relay E, as follows: battery B, 28, 21, s, s', 20, E, 15, d⁶, d⁵, to ground and back to battery. The relay E thereupon locks itself by way of wire 17 and armature e³, and remains in that condition controlled by the relay D'. The energizing of the relay E disconnects wire 18 from its ground connection 15, thus preventing the same trunk from picking up another or the same set of secondary relays 80 after the impulses have been sent. 85

90 Referring to Fig. 7 the connector switch includes the vertical relay V which responding to impulses over the vertical side of the trunk operates the vertical magnet V² which in turn causes the spindle Z carrying the 100 wipers z' and z to step up vertically. The relay V' connected to the rotary side of the trunk responds to rotary impulses and operates the private relay U which in turn causes the mechanically operated side 105 switches to move one point, disconnecting the vertical magnet V² and in its place connecting the rotary magnet V³, and at the same time through the side switch w⁸⁰ connects the tip side of the trunk to a contact 110 in the private relay which, when closed, connects the test relay J. The relay V responding to a second set of impulses over the vertical side of the trunk operates the rotary magnet V³ causing the spindle Z to 115 rotate and bring the wipers to rest on contacts leading to desired lines. The next rotary impulse coming in operates the private relay U in the same manner as before, causing the side switches to make still another 120 movement. This last movement of the side switches disconnects the rotary magnet and in its place connects the relay R' which, when operated closes the circuit of the locking relay X' as follows: battery B wire 309, 125 contact r', armature r, wire 320, relay X', r³, r², to ground and back to battery. Relay X' then completes the circuit of the ringing relay Y. As long as the relay R' is de-energized its circuit is: B, 309, Y', 319, Y, 130

x⁴, x⁵, r¹⁰, r², and ground back to battery. While the relay R' remains energized for other purposes, however, the ringing relay is disabled by the opening of the contacts 5 r², r¹⁰. This occurs during the ringing selection which is now to be described. The relay R' is now in position to be controlled by the third set of impulses coming in over the vertical side of the trunk. This relay 10 controls a set of relays W and these relays in turn control generator current of different frequencies or polarities. All of these relays are self-locking and have a common wire controlling their locking circuits. This 15 common wire 150 leads to a normally open contact in the relay X'. This relay becoming energized at the first impulse of the third set places battery on this wire. The relay R' is also energized at this juncture 20 and after the first impulse its armature drops back and closes the circuit of the relay W⁴ through the normally closed contacts of the relay W⁴, its circuit being as follows: B, 309, x³, x², r⁶, r⁷, 315, w', w², W⁴ and 25 ground back to battery. It will be noted that relay X' remains locked as long as the switch is "off normal" and the called subscriber has not answered, on the following path: B, 309, r⁷, r, 320, X', x, 313, z², z³ and 30 ground back to battery. When the subscriber answers, relay R responds, opens the contacts r, r', and then the relay X' is released but not before. The next impulse operating the relay R' closes the circuit of the 35 relay W⁵ through the contacts of the relay W⁴ and the normally closed back contact of the relay W⁶, and after the second impulse the front contact of the relay W⁶ is closed through the contacts of the relay w⁵. At 40 the third impulse the circuit of the relay W⁷ is closed through the contacts of the relays W⁴ and W⁶ and the normally closed contacts of the relay W⁸; at the end of the third impulse the circuit of the relay W⁸ is closed 45 through the contacts of the relays W⁷ and W⁹ and the normally closed contacts of the relay W¹⁰. At the fourth impulse the circuit of the relay W⁹ is closed through the contacts of the relays W⁸, W¹⁰ and W¹¹. It 50 will be seen from the foregoing description that I have a set of step by step relays controlled by the relay R', the first relay of the set becoming energized when the relay R' becomes deenergized, the second relay becomes energized when the relay R' becomes energized the second time, and the third relay becoming energized when the relay R' becomes energized the third time, and so on. This system of relays can be carried on indefinitely. The relay W⁵ becoming energized disconnects generator G' and in place 55 connects the generator G² to a contact in the ringing relay Y, and the relay W⁷ becoming energized disconnects the generator G² and in its place connects the generator G³ and

the relay W⁹ becoming energized disconnects the generator G³, and in its place connects generator G⁴.

Battery current is supplied to the called subscriber through the relay R and retardation coil I which are normally connected to the calling end of the trunk. The locking circuit of the relay X' is controlled jointly by the normally closed contacts of the relay R and the normally open contacts z² and z³ 70 controlled by the spindle Z. If the called subscriber answers, the relay R becomes energized, disconnecting the relay X' which in turn cuts off the ringing relay Y. If the called subscriber does not answer, the relay X' is disconnected when the calling subscriber hangs up his telephone disconnecting the switch Z which upon return to its normal position opens the contact springs z² and z³. These contact springs are shown in 80 Fig. 7 as arranged beneath and in the line of travel of the spindle of the switch, which is supposed to drop down and open the spring when restored or in inactive position. The calling subscriber at the end of the conversation automatically places battery on both sides of the trunk circuit operating the relays V and V' simultaneously, the action of which closes the circuit of the test relay J which in turn closes the circuit of the 85 release magnet J'. Battery is placed on both sides of the trunk circuit by the combination of relays in the talking trunk circuit as follows: During conversation the relays D, D' and E remain energized. When the 90 subscriber hangs up his telephone the relay D is the first to fall back or become deenergized which places battery through its normally closed contacts to the contacts in the relay E and from there to the trunk circuit. 95 The next relay to drop back or to become deenergized is the relay D' which is kept energized longer than the relay D on account of being in series with the line cut-off relay through the primary selector sets. After 100 the relay D' becomes deenergized the relay E is disconnected and thus battery is removed from both sides of the trunk. 105 Referring now to Fig. 8, which is a modification of Fig. 6, the talking trunk is, practically the same as shown in Fig. 6 consisting of the tip and sleeve relays D and D', the starting relay E and repeating relays S and S'. In this case the tip relay D is 110 normally connected to ground, and the starting relay E instead of being controlled by the action of the relay S is controlled directly by the relay T which is in series with it when the talking trunk is connected to the secondary set. This relay E is provided 115 with a make before break contact and when operated locks itself and is disconnected from the wire 32, leaving it clear for sending impulses to the relay S. In the secondary set I have only provided a single signal 120 125 130

lamp L having omitted the guard lamp L' shown in Fig. 6. The locking contact of the relay T is provided with a resistance coil I^{10} . This coil prevents a short circuit when the two relays T and E are placed in series as the locking contacts of the relay E is connected directly to battery through the contact of the relay D' and if the locking contact of the relay T were connected directly to ground there would be nothing to prevent a short circuit. In this modification I also omit the relay H' shown in Fig. 6, but in Fig. 9, which is a modification of Fig. 5, I have added the magnet X¹⁰.

Referring now to Fig. 9, in place of the motor I have substituted a clutch which is controlled by the magnet X¹⁰. This magnet is controlled by the starting button in a manner similar to that in which the motor is controlled. The wheel Q²⁵ instead of having an insulating point and one wiper or pen is provided with an insulated ridge upon which the contact spring q²⁰ normally rests and at the same time is in connection with the spring q¹⁰. The contact spring q³⁰ immediately under the spring q²⁰ is normally open. The clutch is operated and controlled in the following manner: The operator upon getting the number desired pushes the starting button K₂' which energizes the magnet X¹⁰ and also the relay H, Fig. 8. The relay H becoming energized extinguishes the lamp L. The operation of the magnet X¹⁰ attracts the arm or lever x²⁰ which engaging the movable clutch x²⁰ brings it into engagement with the constantly rotating clutch x²⁰. This action causes the various signal wheels to rotate in the same manner and at the same speed as the similar wheels in Fig. 5 are operated by the motor. As soon as the wheel Q²⁵ starts to rotate the contacts q²⁰ and q³⁰ are closed. The contact q³⁰ is connected to the winding of the magnet X¹⁰ and also to the relay H, Fig. 8. The contact q²⁰ is connected directly to battery B, while the spring q¹⁰ is connected to the winding of the relay T, Fig. 8. It of course follows that both the relay H and the magnet X¹⁰ will remain energized while the wheel Q²⁵ is rotating and until the insulated ridge again engages the contact spring q²⁰. The relay T is held energized after the contacts q¹⁰ and q²⁰ are broken by the relay H, as the winding of the relay T is connected to a contact in this relay. After one complete rotation or when the ridge engages the spring q²⁰ the magnet X¹⁰ as well as that of the relay H becomes deenergized the impulse wheels ceasing to rotate and the secondary set disconnected from the talking trunk. The number wheels and impulse keys are the same as in Fig. 5, and need not be described. In this specification a description of the operation will include Figs. 5 and 6 and an understanding of the opera-

tion of the circuits shown in those figures will enable anyone to understand the circuits of the modifications shown in Figs. 8 and 9.

I will now describe the complete operation of my system, tracing a connection from the calling to the called subscriber, assuming that subscriber A², in Fig. 1, is the calling subscriber. When he takes down his receiver his line circuit, 1—2, is closed, the relay M pulls up (and assuming that all connective apparatus is idle) the relays N and P², in Figs. 2 and 4, pull up, their return wires, 60 and 54 being normally closed through the contact of the relay D₂, Fig. 6. The extension wires from the cut-off relay M' are thus prolonged by way of contacts 502 and wires 12 to the trunk 30—31 in Fig. 4, and so on to the same wires in Fig. 6. Current immediately flows from main battery B in Fig. 6 through the sleeve relay D' and back through the sleeve side of the trunk to the cut-off relay M' to ground. The cut-off relay thereupon immediately pulls up putting the subscriber's line on to the extensions and so on to the trunk whereupon the tip relay D of the trunk pulls up. This closes battery to the wire 14 and to the locking wire 57, the wire 14 being previously connected to battery through the back contact e² of the relay E. The relays N and P² remain locked therefore subject to the control of the relay D which is controlled directly by the calling subscriber.

Drawings accompanying this specification only show one talking trunk, but it is of course understood that the full percentage is to be provided and that the secondary set shown in Fig. 6 can be connected to any one of the talking trunks. When the relay D' pulls up it puts battery on the relay D² which pulls up and cuts off all the return wires 54 of the selector relays N, P, etc., of its set. The trunk is thus disabled for any other call. At the same time current passes through the wire 600 to the armature of a relay (11' of Fig. 22) in the next trunk corresponding to the relay D', through a back contact thereof and so on to the relay 1D² corresponding to the relay D₂ which immediately pulls up and places battery on the actuating windings of the relays 1N, 1P, etc., of its set. The next call coming in would be connected to the second trunk, and so on. The energizing of the relay D' in addition to connecting ground to the winding of the relay D also places ground on the starting wires 18 and 118 of the secondary operator's set through the normally closed contacts e and e' of the relay E. As the secondary set is idle the tens relay F as well as the units relay F' will become energized. The energizing of these two relays connects the wires 32 and 33 leading to the relays S and S' respectively, to the wires 40 and 39.

secondary set. The first thing that happens is the relay T is connected in series with the relay S by the following path: battery B, 29, 42, h⁹, h¹⁰, 41, 38, 36, 43, T, t², t¹, 44, h², h³, 40, 32, S, to ground. The relay T becoming energized locks itself through the contacts t² and t¹, opening the contacts t¹ and t², thus removing itself from the wire 40. The relay S being momentarily energized at 10 tracts its armature and closes the circuit of the relay E by the following path: battery B, 28, 21, s, s¹, 20, E, 15, d⁶, d⁵, to ground. The relay E thereupon locks itself through the contacts e⁴ and e³, as the contact e⁴ is 15 connected to the winding and the contact e³ is connected to battery. The energizing of this relay disconnects the starting wires 18 and 118 leaving them free from further interruptions by this trunk, and also takes 20 battery off the locking wire 14, but as the relay D has become energized, another path to battery has been established thereby through the contacts d³, d⁴, so the potential of the wire remains constant. The opening 25 of the starting circuit removes ground from the actuating windings of the relays F and F' and they are now held energized through their locking windings by the following path: battery B, 29, 42, h⁹, h¹⁰, 41, 38, F' 30 to ground, the relay F being held up in parallel by the extension wire 36. The energizing of the relay T closes the circuit of the lamp L causing it to glow. The operator perceiving the signal depresses the 35 talking button K* connecting her talking set across the wires 32 and 33 through the contacts of the relays F and F'. This talking set being bridged across the wires 32 and 33 closes the circuits of the relays S and S', thus connecting the talking set to the trunk 40 wires through the contacts s², s³, and s⁷, s⁸, respectively. Through these two relays battery current is supplied to the operator's set, and at the same time they connect the set 45 across the trunk wires enabling her to converse with the calling subscriber. The action of these relays at this time places battery on both trunk wires 30_a and 31_a through the contacts s⁴, s⁵, and s⁹, s¹⁰, respectively. Battery current going over both 50 sides of the trunk at the same time, restores to normal the switching mechanism of Fig. 7 in case it had been left in an unrestored position through some fault of the relays 55 when the trunk was last used. The operator now being connected to the calling subscriber and asking for the number depresses the buttons of her key set corresponding to the number desired. For illustration, suppose the number asked for was 43-3, the 60 first two digits representing the telephone line number and the last digit representing the signaling number as I wish to illustrate the manner of selective party-line ringing. 65 The operator depresses the fourth key in the set K', the third key in the set K², and the third key in the set K³. Having thus set up the number the operator closes the starting key K² thereupon closing the circuit of the relay H, Fig. 6, by the following path: battery B, 210, 73, 790, 82, H to ground. The energizing of this relay closes the circuit of the relay H' by the following path: battery B, 29, 42, h, h', H' to ground. The energizing of the relay H' opens the locking circuit of the relays F and F' but the circuit is maintained through the contacts h⁴ and h⁵ of the relay H. The action of the relay H' closes the circuit of the lamp L' causing it to glow. It also closes the circuit of the motor, Fig. 5, through the contacts h⁶ and h⁷. Referring to Fig. 5 the starting of the motor X causes the impulse wheels to rotate. At the first movement of the wheels, the pen q⁶ rides on the metal portion of the wheel Q²⁵, thus maintaining the circuit of the motor X, after the starting button is released. The common wire 79 receives the vertical impulses, that is to say, impulses from the wheels Q', Q², Q³, Q⁴, etc. From this wire the impulses are conveyed to the relay S through the contacts of the relays F and F'. The rotary impulses, or the impulses from the wheel Q are conveyed to the relay S' through the same relays. The first set of impulses to be received by the relay S are those transmitted from the pen q' of the wheel Q⁴. These impulses pass through the contacts of the fourth button of the set K', the next impulse is a rotary impulse sent to the relay S' by the wheel Q. The second set of vertical impulses are sent to the relay S by the pen q² of the wheel Q³ through the contacts of the third button of the set K², then follows another rotary impulse from the wheel Q. The third set of impulses are sent from the pen q³ of the wheel Q² through the contact of the third button of the set K³, then follows the third rotary impulse. After the last set of impulses, or after one complete revolution, the pen q⁶ of the wheel Q²⁵ rests on the insulated portion and the relay H becomes deenergized. The deenergizing of this relay opens the locking circuits of the relays F, F' and T, thereby disconnecting the secondary set from the talking trunk. The deenergizing of the relay H releases the relay H' and extinguishes both lamps L and L'. It, of course follows, that as the operator's talking set is connected to the secondary set and the secondary set is disconnected from the talking trunk the operator is prevented listening in on the trunk during conversation. The secondary set is only connected to the talking trunk while the number is being taken, and while the impulses are being sent. Referring to Fig. 7 I will show how these impulses from the secondary set which op-

erate the relays S and S' in Fig. 6 control the switching mechanism in this figure. I have already shown how the calling subscriber is automatically connected to a secondary set through a talking trunk, the secondary set simply containing the operator's set and impulse transmitter. I have also shown how these impulses from the various wheels affect the relays S and S'. The first set of impulses which, in this case number four causes the relays S to attract its armature four times and send that number of impulses over the wire 30^a through the contacts s⁴ and s⁵. These impulses coming in over what is known as the vertical side of the trunk operate the vertical relay V which in turn closes the circuit of the vertical magnet V² by the following path: ground, v³, v², w, w¹, 306, switch arm w^{5c}, 321, V², 309, to battery B. The operation of this magnet causes the spindle Z carrying the wipers z and z' to step up vertically opposite a row of contacts corresponding to the number of impulses sent from the secondary set. After this first set of impulses a rotary impulse is placed on the wire 31^c or the rotary side of the trunk by the action of the relay S'. This impulse operates the relay V', which in turn closes the circuit of the private relay U which causes the side switch to move one step, placing the various arms w⁵⁰, w⁶⁰, w⁷⁰ and w⁸⁰ on the second contacts. The movement of the arm w⁵⁰ disconnects the vertical magnet V² and in its place connects the rotary magnet V³, while the operation of the arm w⁸⁰ connects or places the test relay J in position to test the tip side of the line. The second set of impulses numbering three, operates the relay V which in turn closes the circuit of the rotary magnet V³ causing the spindle Z to rotate and bring the wipers to rest on contacts leading to the desired line. The second rotary impulse now coming in operates the relay v' which closes the circuit of the private relay U causing the side switch to take another step bringing the switch arms to rest on the third contacts. During this second rotary impulse while the relay U is energized the test relay J is connected directly to the tip side of the line and if the line were busy the relay J would become energized and closing the circuit of the release magnet J' restore the switch to its normal position. We will take it for granted that the called line is idle, so therefore the switch arms rest on their respective contacts. The switch arm w⁵⁰ disconnects the rotary magnet V³ and in its place connects the relay R'. The switch arms w⁶⁰ and w⁷⁰ close their respective trunk circuits while the switch arm w⁸⁰ disconnects the test relay from the tip side of the line or trunk. The calling subscriber is now connected to line number 43. The third set of impulses now coming in operate the relay V which in

turn closes the circuit of the relay R'. The first one of three impulses affecting this relay causes it to close the circuit of the relay X' by the following path: ground, r², r¹, X', 320, r', r, 309, to battery B. This relay now locks itself through the contacts x and x', the contact x being connected to ground through the springs z² and z³ which are controlled by the switch spindle. The winding of the relay X' is connected to battery through the normally closed contacts r, r' of the relay R. Battery is now placed on the locking contacts of the ringing relay set W through the common wire 150 and the contacts x² and x³ of the relay X'. The number of impulses in this last set are three which correspond to the ringing number of the desired party.

The first impulse affecting the relay R' does not affect any other relays in the ringing set W, but immediately after the first impulse when the relay R' drops back the circuit of the relay W¹ is closed by the following path: battery B, 309, 312, x², x³, r⁶, r⁷, 315, w¹, w², W¹, to ground. The second impulse coming in operating the relay R' closes the circuit of the relay W⁵ by the following path: battery B, 309, 312, x², x³, r⁶, r⁵, 314, w⁶, w⁵, w¹³, w¹⁴, w⁵, to ground. The operation of the relay W⁵ disconnects the first generator G¹ and connects the generator G² in its place to the normally open contact in the ringing relay Y. Immediately after the second impulse the relay R' dropping back closes the circuit of the relay W⁶ through the path already described to wire 315 and from there through w¹, w, w⁸, w⁹, W⁶, to ground. The third impulse coming in closes the circuit of the relay W⁷ through the path already described to wire 314 and from there through w⁶, w⁵, w¹³, w¹², w²¹, w²², W⁷, to ground. The operation of the relay W⁷ disconnects generator G² and in its place connects the generator G³ which is of proper frequency or polarity to ring the bell at the desired station. Immediately after the third impulse the circuit of the relay W⁸ is closed in a manner similar to that already described in connection with the other relays.

The proper generator current is now placed on the contacts in the ringing relay Y. One terminal of the relay Y is connected directly to an interrupting machine Y' and the interrupting machine itself is connected directly to battery. The other terminal of the relay is connected to ground through the normally closed contacts r¹⁰ and r² of the relay R' in series with the contacts x⁴ and x⁵ of the relay X'. While the ringing impulses are being sent and the proper relay in the ringing set W is being selected the relay Y is not affected on account of the rapid making and breaking of the contacts r¹⁰ and r². After the impulses have been sent and the relay R' is in its normal posi-

130

tion the circuit of the relay Y is closed and opened through the interrupting machine Y'. When its circuit is closed the relay Y opens the answering end of the trunk and places generator current on the calling end of the trunk. This current is placed on the line intermittently and during one of these intermissions when the relay Y is deenergized and the called subscriber removes his telephone the relay R becomes energized and opening the contacts r and r' releases the relay X' which in turn opens the circuit of the ringing relay Y, thus preventing any further generator current being placed on the line. The retardation, or resistance coil I is provided to hold up the cut-off relay of the line while generator current is being sent over the line. All of the generators have one terminal connected to battery and this coil having one of its terminals connected to battery insures a metallic ringing circuit.

From the foregoing description it will be seen that the two subscribers are provided with a clear talking circuit, battery current being supplied to the called subscriber from the connector switch and battery supplied to the calling subscriber from the trunk. In this present arrangement there are two sets of condensers in this talking circuit and also an additional bridge caused by the relays V and V' which are not needed at this juncture. The relay X' which is released when the called subscriber answers also unlocks the relays in the ringing set W thus preventing a waste of current. At the end of the conversation the calling subscriber hanging up his telephone deenergizes the relay D and this relay dropping back opens the locking wire 14, releasing the relays N and P² which upon falling back open the trunk circuit disconnecting the relay D' and the line cut-off relay M'. The relay D being the first to fall back places battery on both sides of the trunk leading to the switching mechanism through the contacts e^5 , e^6 and e^7 , e^8 . The relay D' is the next relay to drop back thereby releasing the relay E, removing the battery from both sides of the trunk. From this combination it will be seen that a momentary impulse has been placed simultaneously on both trunk wires. Referring now to Fig. 7 this momentary impulse operates the relays V and V' closing the circuit of the relay J by the following path: ground, v , v' , J, battery B. This latter relay operating closes the contacts j and j' energizing the release magnet J' thereby restoring the switch to its normal position.

It will not be necessary to describe the full operation of the modifications shown in Figs. 8 and 9 as these can simply be substituted in place of Figs. 5 and 6 and the results will be the same. I have preferred in giving a description of the full operation of my system to use Figs. 5 and 6 as I have

actually had the circuits as shown wired up and in full operation. The only practical difference between the figures used and the modifications themselves is that in place of a motor driving the impulse wheels I have shown the wheels being driven by constantly rotating shaft when the magnetically controlled friction clutch is operated.

From the foregoing description the following points will be observed: First, the calling subscriber is automatically connected to an idle talking trunk by means of a primary relay set. Second, from the talking trunk he is automatically connected to an idle operator's set by means of a secondary relay set. Third, the operator simply depresses a button to inquire the number. Fourth, after getting the number she simply sets it up by depressing the proper buttons, after which the called party is automatically connected to the talking trunk. Fifth, after the number has been transmitted the secondary set as well as the operator is disconnected from the talking trunk thus insuring positive secrecy. Sixth, the ringing is done automatically from the connector switch. Seventh, party line ringing is provided for so that any desired method of selective ringing can be employed. Eighth, the disconnecting is done automatically when the subscribers have finished talking. Ninth, the operator has no means of knowing where or from whom a call originates, so there is no chance for favoritism, and all parties in this case will receive the same amount of attention.

The operation of setting up the number by pressing the proper button is sub-consciously controlled after sufficient practice has been had, as in any other case of purely manual dexterity such as typewriting. By actual trial the time consumed in receiving and setting up a number having five digits averages about 2.9 seconds. A very little figuring will suffice to show that on a three second basis the operator could handle 20 calls per minute, or 1200 per hour. Taking one-half of this, I fix 600 calls per hour as a standard maximum, and I furnish the operators with sufficient apparatus for this and no more.

It will be noticed by referring to the drawings that in the mechanical figures I have shown four rows of buttons per set and four additional selective ringing buttons which would serve for a 10,000 line system, while in the circuit drawings I have only shown two rows of buttons and four additional selective ringing buttons. I have omitted adding these extra buttons to the circuit drawings for sake of simplicity. To add the full equipment of buttons would mean inserting first and second selector switches and describing them in detail. The invention is shown fully in connection with

a hundred line system, such as I have described and additional apparatus would simply require repetition.

Fig. 19 shows a modification in the apparatus used for the primary and secondary selector functions in an exchange built according to the principles of my invention. In Fig. 19 the first selector set of relays is displaced by a mechanically-driven shaft 10 moving wipers over fixed contacts, the wipers being trunk terminals and the fixed contacts line terminals. In this way the trunk constantly searches for a calling line and stops upon a calling line when such a 15 line is found, the result being the same as with the set of selector relays in Figs. 2, 3 and 4. The secondary set of relays is replaced by a similar power-driven call-seeking switch.

20 Figs. 5, 7 and 19 may be attached to form a diagram of the complete operating system. The operation is as follows: Shaft 601, belonging to trunk 30-31, revolves continuously when the trunk is idle, and 25 carries its wipers 603-604-605 over waiting contacts of the lines served by the group of trunks of which the trunk 30-31 is one. When a subscriber, as at substation 606, calls, current flows over path B, 607, 608, 30 contact and armature of 609, 610, 606, 611, armature and contact of 609, 612 and earth, energizing relay 608 and closing its contact, thus extending the battery potential to 35 a waiting contact 613 accessible to wiper 603. When wiper 603 in the course of its travel next makes connection with waiting contact 613, current flows over the path B, 607, armature and contact of 608, 613, 603, 616, armature and contact of D, 617, magnet 618 and earth, which energizes clutch magnet 618. Clutch magnet 618 operates its clutch 619 to disconnect the shaft 601 from the belt-driven pulley 620, thereby 40 stopping the shaft 601 with the wipers 45 603-604-605 in connection with the waiting contacts 613-614-615, respectively. Current now flows over the path B, 621, D', 50 31, 605, 615, 609 and earth, energizing D' and 609; by the energization of relay 609 line conductors 610-611 are disconnected from relay 608 and wire 612 respectively and are extended through contacts 614-615 and wipers 604-605 to trunk conductors 30-31 respectively. Current now flows over path B, 55 621, D', 31, 605, 615, contact and armature of 609, 611, 606, 610, armature and contact of 609, 614, 604, 30, D and ground, energizing D. The operation of armature 622 of relay D closes path for current through 60 B, 621, 623, 622, 617, 618 and ground, maintaining the energization of clutch relay 618, the previous path for energizing that magnet having been broken by deenergization 65 of relay 608 following the energization of

relay 609. This is the complete cycle of operations for the connection of an idle trunk to a calling line. 65

Passing now to the connection of an idle operator's set, as *Kai*, to the trunk 30-31 which now is a calling trunk, we have similar apparatus in the shaft 624 and clutch magnet 625. The energization of relay D' extends the ground upon its armature over conductors 626, 627 to waiting contact 628. When wiper 629 makes connection with contact 628, path is closed for current as follows: B, 630, 631, 625, 632, armature and contact of T, 634, 629, 628, 627, armature and contact of F, 626, contact and armature of D and ground. This energizes clutch 70 magnet 625 and stops the motion of the wipers 629-635-636, holding them in connection with contacts 628-637 and 638 respectively. Current now flows over path B, 75 630, armature and contact of H', 639, 640, T, 80 closed contact of T, 633, 636, 638, S and earth, energizing T which locks over its armature *t* and which by its armature *t'* furnishes ground for clutch magnet 625. By 85 this energization of relay S, also, current flows over path B, 621, 641, armature and contact of S, 692, F, contact and armature of D' and ground, energizing relay F which locks over the path B, 621, 642, F, armature and contact of D' and ground. This energization and locking of relay F breaks the 90 connection between wires 626-627 and takes the calling condition off of waiting contact 628 so that other operators' trunks will not 95 find the main trunk 30-31 calling, and therefore will not stop in connection with it. The operator now answers by key *Kai* and handles the call as in Fig. 6, the device of Fig. 5, controlling the relays S S' as hereinbefore discussed, and those relays in turn 100 controlling the device of Fig. 7, as hereinbefore discussed.

Upon the completion of the cycle of the wheel *Q^{2x}*, the battery potential is broken from relay H, and by release of its armature 643 the relay T is unlocked. By the unlocking of relay T, the clutch magnet 625 is deenergized and shaft 624 moves its wipers out of contact with the main trunk just served. Upon the conclusion of the 110 conversation the hanging up of the telephone at 606 breaks the circuit for current flowing through relay D, and by the release of its armatures the battery B is closed over wires 621, 623 to wires 644-645 which, 115 through contacts of relay F, are connected to wires 30x-31x. The deenergization of D deenergizes magnet 618 which operates its clutch to connect shaft 601 to the source of power, and the wipers thus are moved out 120 of connection with the served line. The breaking of wiper 605 from contact 615 125 interrupts the current through relay D'. By

deenergization of D', F is deenergized, which in turn breaks wires 644-645 from 30e-31a. The interval of battery connection to 30e-31a has restored to normal, 5 the switching mechanism of Fig. 7 as hereinbefore described, and all parts of the system are again in normal condition in readiness for the next call.

It will have been observed that by virtue 10 of the employment of relay primary and secondary sets, that the connection of a calling line with an idle operator is both instantaneous and certain, a train of relays pulling up and completing a talking circuit 15 to a trunk and to a waiting operator the instant that the subscriber removes his receiver from its hook. The commercial advantage of instantaneous answering service will be appreciated by everyone, and the 20 large amount of time thus saved subscribers more than warrants the use of this system in a large majority of instances. Furthermore the certainty of the relay selectors over traveling switches will be readily appreciated by those skilled in the art. Traveling switches cannot be adjusted for uniformity and certainty of contact and beside their circuits frequently contain relays which operate upon a margin, as it is commonly expressed, some relays pulling up on 25 greater or less current than others, or only when certain series or shunt resistances or the like are removed from their circuits. In the case of the relay selector sets utilized 30 in applicant's invention, there is uniform certainty of contact and no marginal operation, the relays being either fully energized or completely deenergized and their contacts either open or solidly closed. The result is 35 a positiveness and surety of operation which carries the efficiency of the system to a very high point.

I do not herein claim broadly the system 40 of tri-headed trunks or secondary distributing means for operators' trunks, inasmuch as said subjects matter are claimed in my copending applications Serial Nos. 369, 201, filed April 20, 1907; 383,874, filed July 15, 1907; and 383,875, filed July 15, 1907. As 45 will be readily understood from the foregoing description, this application is intended to cover particularly the use of relay primary, and relay secondary, selector sets, and their auxiliaries, in the system set forth. 50 Having thus described my invention, what I claim and desire to secure by Letters Patent is:

1. In a telephone exchange system, the combination of the following instrumentalities: a plurality of line circuits, automatic switching means for interconnecting the circuits, an operator's controlling apparatus and telephone, and automatic means comprising a set of selective relays for connect-

ing the said controlling apparatus and telephone with said interconnecting means and with a calling line, respectively, substantially as described. 55

2. In a telephone exchange system, a plurality of line circuits and means for interconnecting them comprising the following instrumentalities: banks of relays actuated when lines are calling to connect therewith, automatic switches associated therewith and adapted to select the lines wanted, controlling apparatus for said switches adapted to be manually actuated at the central office or exchange, and automatic switching apparatus for connecting the same to the selecting switch circuits, substantially as described. 70 75 80

3. In a telephone exchange system, a plurality of line circuits and means for interconnecting them comprising the following instrumentalities: automatic answering switches actuated when lines are calling to connect therewith, other automatic switches associated therewith and adapted to select the lines wanted, groups of relays for selecting and connecting with any of the aforesaid switch circuits, and operator's sending apparatus associated therewith and brought thereby into proper relation with the main switches to control the same, substantially as described. 85 90 95

4. In a telephone exchange system, a plurality of subscriber's lines and connecting apparatus therefor comprising the following instrumentalities: groups of relays adapted to connect with the line calling together with other automatic switches adapted to connect with the line wanted, circuits interconnecting the same, an operator's controlling apparatus therefor, and automatic means for connecting the same thereto when a calling line is connected thereto and for disconnecting the same therefrom when the wanted subscriber's connection is completed, substantially as described. 100 105 110

5. In a telephone exchange system, the combination of a plurality of lines to be interconnected, with primary selector switches for answering the calls and initiating connections, line selectors and connectors for completing the connection, secondary selectors comprising sets of digitally associated relays for bringing an operator's set into connection with the circuits of the primary and line switches, and means included in said set whereby an operator may control the same, substantially as described. 115 120

6. In a telephone exchange system, a plurality of circuits to be interconnected and means for interconnecting them comprising the following instrumentalities: primary selector relays, secondary selector switches, and line selecting and calling switches, together with controlling apparatus acting upon the selecting switches through the sec-

- ondary selector connection as determined by an operator, substantially as described.
7. In a telephone exchange system, a plurality of line circuits to be interconnected, together with switching units for interconnecting them comprising automatic primary selector switches for connecting a switching unit with a calling line, automatic secondary selector relay sets for connecting a switching unit with an operator's position, and line selecting switches for connecting a switching unit with a wanted line, together with operator's controlling apparatus therefor, substantially as described.
- 15 8. In a telephone exchange system, the combination of a plurality of line circuits and means for interconnecting them, comprising automatic primary selecting digital relays together with automatic switching devices arranged to connect with called lines, operator's controlling apparatus for the latter, and means for automatically connecting and disconnecting the same thereto and therefrom, substantially as described.
- 25 9. In a telephone exchange system, a plurality of line circuits; a plurality of connecting trunks; banks of automatic selective relays for connecting said trunks to calling lines; other automatic switches for connecting said trunks to wanted lines; and other banks of automatic selective relays for connecting said trunks to operator's controlling devices, substantially as described.
- 35 10. In a telephone exchange system, a plurality of line circuits; a plurality of connecting trunks; banks of automatic selective relays for connecting said trunks to calling lines; automatic means for connecting said trunks to wanted lines; operator's controlling means for controlling said second means; and banks of automatic selective relays for associating said trunks individually with said operator's controlling means, substantially as described.
- 45 11. In a telephone exchange system, a plurality of line circuits; a plurality of trunks; banks of automatic selective relays for connecting said trunks to calling lines; automatic selective switching devices for connecting said trunks to wanted lines; operator's controlling means for actuating said selective switching devices; and banks of automatic selective relays for associating said trunks individually with said operator's controlling means, substantially as described.
- 55 12. In a telephone exchange system, a plurality of line circuits; a plurality of connecting trunks; and primary selector sets of tens and units relays for connecting the same to calling lines; other automatic switches for connecting the same to wanted lines; means controlled by an operator for actuating said second automatic switches; and secondary selector sets of tens and units relays for connecting said operator-con-
- trolled means to a trunk upon said trunk's being connected to a calling line, substantially as described.
13. In a telephone exchange system, a plurality of lines; a plurality of trunks; a plurality of operator's selective trunk-controlling devices; a set of digitally arranged relays for connecting a calling line to one of said trunks; and automatic means for causing said trunk to connect with an idle one of said operator's controlling devices when said trunk becomes connected with by a calling line, substantially as described.
- 70 14. In a telephone exchange system, a plurality of lines; a plurality of trunks; a plurality of operator's trunk-controlling devices; banks of coacting relays associated with the trunks together with means responsive to the closure of the calling line circuit to connect the same automatically through selected relays in the banks with the trunks; automatic means for causing said trunk to connect with an idle one of said operator's controlling devices when said trunk becomes connected with by a calling line; and selective switching devices associated with each of said trunks and coöperating with said operator's controlling means to connect a trunk to a wanted line in response to operator's control, substantially as described.
- 75 15. In a telephone exchange system, a plurality of lines; a plurality of trunks; a plurality of operator's trunk-controlling devices; sets of selecting relays associated with and individual to the respective trunks and adapted to be directly controlled through the closure of the subscribers' lines when calling to connect the same to the trunks individually; automatic means for causing said trunk to connect with an idle one of said operator's controlling devices when said trunk becomes connected with by a calling line; and means responsive to said operator's trunk-controlling device for connecting said trunks with desired lines, substantially as described.
- 80 16. In a telephone exchange system, a plurality of lines; a plurality of trunks for interconnecting said lines; automatic switches for connecting one of said lines that originates a call with an idle one of said trunks; a plurality of operator's controlling mechanisms; and banks of automatic selective relays each individual to an operator's controlling mechanism for enabling a trunk so chosen to select and connect with an idle one of said controlling mechanisms, substantially as described.
- 85 17. In a telephone exchange system, a plurality of lines; a plurality of trunks for interconnecting said lines; banks of digitally arranged relays responsive to control from the subscribers' lines for connecting one of said lines that originates a call with
- 90 95 100 105 110 115 120 125 130

- an idle one of said trunks; means to remove said relays from the control of the line when said connection is effected; a plurality of operator's controlling mechanisms; other 5 automatic switches for enabling a trunk so chosen to select and connect with an idle one of said controlling mechanisms; switching devices associated with said trunks for connecting said trunks to wanted lines, and connecting 10 operating with said operator's controlling mechanisms, substantially as described. 70
18. In a telephone system, the combination of subscriber's lines; link circuits and automatic switches adapted to interconnect 15 said lines; operator's selective equipments; and secondary selector sets of relays adapted to connect to an operator's equipment a link circuit previously connected to a line, substantially as described. 75
19. In a telephone system, the combination of subscriber's lines; trunks and automatic switches adapted to interconnect said lines; operator's selective equipments; and secondary selective sets of relays responsive 20 to control from the trunks and adapted to connect to an operator's equipment a trunk previously connected to a calling line, substantially as described. 80
20. In a telephone system, the combination 25 of subscriber's lines; automatic switching link circuits adapted to connect with said lines; operator's selective equipments; secondary selector sets of relays responsive to control from the trunks adapted to connect to an operator's equipment a switching 30 link circuit previously connected to a line, and means for removing the control of said secondary sets of relays from the trunks when connection has been completed, substantially as described. 85
21. In a telephone system, lines; trunks; line controlled means for connecting a trunk with a calling line; operators' sets less in number than the number of trunks; secondary 35 means comprising banks of coating relays for connecting a trunk with an operator's set; and a relay associated with each trunk for rendering said secondary means operative, said relay being controlled in the 40 connection of the trunk with the calling line, substantially as described. 90
22. In a telephone system, lines; trunks; line controlled means for connecting a trunk with a calling line; secondary means comprising coating banks of tens and units relays for connecting a trunk with an operator's set; a relay associated with the trunk for rendering said secondary means operative; and a circuit including said relay and 45 a connected telephone line whereby said relay is energized only when said trunk is connected with a calling telephone line, substantially as described. 95
23. In a telephone system, lines; trunks; 50 automatic means for connecting a trunk with a calling line; automatic secondary means comprising tens and units relays for connecting a trunk with an operator's set; a relay associated with the trunk, for rendering said automatic secondary means operative; and a circuit including said relay and a connected telephone line whereby said relay is energized only when said trunk is connected with a calling telephone line, together with means actuated when the operator's set is connected with a trunk to render available another operator's set for connection with the succeeding trunk, substantially as described. 100
24. In a telephone system, the combination of subscriber's lines; trunks; means for interconnecting calling lines and trunks; operator's selective trunk-control equipments; and digital sets of relays for connecting calling trunks with an operator's trunk-control equipments, together with means controlled in the operation of connection of any trunk control equipment with any trunk to transfer the connecting function to an idle set of relays, substantially as described. 105
25. In a telephone system, the combination of subscriber's lines; trunks; means for interconnecting calling lines and trunks; operator's trunk-control equipments; and a digital set of relays for connecting a calling trunk with an operator's trunk-control equipment, said means acting automatically after a desired connection is established to disconnect the operator's equipment from the trunk, substantially as described. 110
26. In a telephone system the combination of subscriber's lines; trunks and switches coöperating with the terminals of said subscriber's lines; operator's equipments for actuating said switches; secondary selectors comprising digital sets of relays associated with said trunks and with said operator's equipments and adapted to connect an idle operator's equipment with a trunk requiring attention; and means for automatically disconnecting the operator's equipment from a trunk after the desired connection has been set up, substantially as described. 115
27. In a telephone system, the combination of subscriber's lines; trunks; means for interconnecting calling lines and trunks; operator's selective trunk-control equipments; and digital sets of selective relays for connecting a calling trunk with an operator's trunk-control equipment, substantially as described. 120
28. In a telephone system, the combination of subscriber's lines; trunks; means for interconnecting calling lines and trunks; automatic switching means associated with said trunks for selecting and connecting with a line to be called; operator's trunk control equipments; and selective switching means comprising a set of tens and units relays for connecting a calling trunk with 125
- 65

an operator's trunk—control equipment, substantially as described.

29. In a telephone system, a plurality of line circuits; a plurality of trunks; automatic switching devices for connecting said trunks to calling lines; automatic selective devices for connecting said trunks to wanted lines; operator's controlling means for actuating said selective switching devices; automatic means comprising a digital set of selective relays for associating said trunks individually with said operator's controlling means; and means for enabling the operator of said controlling means to converse with the subscriber on the calling line, substantially as described.

30. In a telephone system, a plurality of lines; a plurality of trunks; a plurality of operator's selective trunk-controlling devices; means for connecting a calling line to one of said trunks; automatic means comprising a digital set of relays for causing said trunk to connect with an idle one of said operator's controlling devices when said trunk becomes connected with by a calling line; and telephonic circuits between the operator and said calling line, substantially as described.

31. In a telephone exchange system, subscriber's lines, a plurality of connective trunks therefor, a plurality of operators' sets, automatic means comprising a digital relay selector for selectively effecting the connection of any of said trunks with an idle operator's set, means for effecting a com-

pleted connection with the called subscriber through impulses from said operator's set, and a common battery at the central station for supplying talking current to the subscribers' lines and energizing current for effecting the selective connection of the lines with the trunks and of the operators' sets, and for furnishing the actuating current for the automatic connective apparatus.

32. In a telephone exchange system, subscribers' lines, a plurality of connective trunks therefor, digital sets of primary selector relays arranged to connect said trunks with calling lines, a plurality of operators' sets, a digital relay secondary selector set for selectively effecting the connection of any of said trunks with an operator's set when idle, switching apparatus for effecting a completed connection with the called subscriber through impulses from said operator's set, and a common battery at the central station for supplying talking current to the subscriber's lines and energizing current for effecting the selective connection of the lines with the trunks and with the operators' sets and for furnishing the actuating current for said sets of relays and switching apparatus.

In testimony whereof I affix my signature in presence of two witnesses.

EDWARD E. CLEMENT.

Witnesses:

Jos. L. WRIGHT,
E. EDMONSTON, Jr.

It is hereby certified that in Letters Patent No. 1,109,617, granted September 1, 1914, upon the application of Edward E. Clement, of Washington, District of Columbia, for an improvement in "Telephone-Exchange Systems," an error appears in the printed specification requiring correction as follows: Page 17, strike out lines 43-54 and insert the following paragraph:

I do not claim broadly herein the fundamental features of the system disclosed, including primary and secondary distributing means as such; claims therefor being made in my copending application serial No. 858,481, filed August 25, 1914, as a continuation in part of serial No. 327,096, filed July 20, 1906. Related claims are also made in other copending applications as follows: Serial Nos. 369,201, filed April 20, 1907; 383,874, filed July 15, 1907; and 383,875, filed July 15, 1907; and that the said Letters Patent should be read with this correction therein that the same may conform to the record of the case in the Patent Office.

Signed and sealed this 22nd day of September, A. D., 1914.

[SEAL.]

R. F. WHITEHEAD,
Acting Commissioner of Patents.
